UNITED STATES PATENT OFFICE.

CARL J. CARLBERG, OF FALUN, KANSAS.

DESIGN FOR A CULTIVATOR KNIFE OR SHOVEL.

SPECIFICATION forming part of Design No. 18,596, dated September 11, 1888.

Application filed July 31, 1888. Serial No. 281,561. Term of patent 7 years.

To all whom it may concern:

Be it known that I, CARL J. CARLBERG, of Falun, in the county of Saline and State of Kansas, have invented and produced a new 5 and original Design for a Cultivator Knife and Shovel, of which the following is a full, clear, and exact specification.

Reference is had to the accompanying drawings, which form part of this specification, and 10 in which—

Figure 1 is a perspective of my newly-designed cultivator knife or shovel; and Figs. 2 and 3 are front and side views, respectively, thereof.

15 The shank A, which is of slightly-concave form in a downward direction upon its outer face and inclines laterally inward in a forward direction across said face, joins on its front margin, as by a gentle hollow or curve, b, the 20 upper end of the front cutting-edge, c, of the knife and shovel B. From this point the marginal portion c slopes backwardly and laterally outward to a bottom point, d, and from

this part upward to the inner marginal portion of the shank A the outer facial configuration is rounded, as at e, where it blends with or meets the wing C, which inclines inwardly in a backward direction—that is, in a reverse direction to the knife and shovel B—and which wing C slopes upward in a backward direction 30 in partly curved and straight lines along its lower margin, f, and has its rear end portion slightly curved laterally outward, as at g.

The peculiar twisted and angular configuration of the knife is the leading feature of this 35 design.

I claim—

The design for a cultivator knife and shovel, substantially as described, and shown in the accompanying drawings.

CARL J. CARLBERG.
